UNITED STATES PATENT OFFICE.

LEWIS A. JARVIS, OF GRAND RAPIDS, MICHIGAN.

DESIGN FOR A WATER GAUGE FOR AUTOMOBILE RADIATORS.

Application filed May 1, 1922. Serial No. 2,028. Term of patent 3½ years.

To all whom it may concern:

Be it known that I, LEWIS A. JARVIS, a citizen of the United States, residing at Grand Rapids, county of Kent, State of Michigan, have invented a new, original, and ornamental Design for Water Gauges for Automobile Radiators, of which the following is a specification, reference being had to the accompanying drawing, forming a part thereof.

The figure is a front view of a water gauge for automobile radiators, showing my new design.

I claim:

The ornamental design for a water gauge for automobile radiators, as shown.

LEWIS A. JARVIS.
